Application April 28, 1945, Serial No. 590,753

10 Claims. (Cl. 230—134)

1

This invention relates to centrifugal fans or blowers for heat treating furnaces and the like, and the principal object of the invention is to provide a simple construction that can be readily manufactured from suitable heat and corrosion resisting alloys and will allow appropriate freedom of movement among the parts in expanding and contracting while maintaining dynamic balance of the whole in use.

Generally speaking, this is accomplished by interlocking a plurality of separate, like blades in circular arrangement about a common axis of rotation so that they mutually sustain each other against individual outward movement as they expand and contract in use.

In the accompanying drawings, preferred forms of double inlet and single inlet fans are shown which should be considered merely as examples, for it is fully appreciated that the fundamentals of the invention are susceptible of a great many different embodiments too numerous to illustrate or attempt to describe.

Figs. 1 and 2 are diagrammatic views of a double inlet fan and its associated parts in one form of illustration;

Fig. 3 is a longitudinal sectional view through a double inlet fan and a hollow fan shaft taken on the line 3—3 of Fig. 2;

Fig. 4 is a side elevation of one of the twelve blades used in this particular fan;

Fig. 5 is an edge view of the fan shown in Fig. 4;

Fig. 6 is a face view of one of the hub members used in this fan;

Fig. 7 is a horizontal section through the axis of Fig. 6;

Fig. 8 is a perspective view of one of the pins by which the several blades are interlocked to each other and to the hub members in this fan;

Fig. 9 is a perspective view of a spacer used between the two hub members in this fan as shown in Fig. 8;

Fig. 10 is a half section at right angles to the axis of the fan shown in Fig. 3 and a half end elevation of that fan;

Fig. 11 is a side elevation of one-half of one of the shroud rings, two of which are carried by the blades as shown in Figs. 3 and 10;

Fig. 12 is a view similar to Fig. 4 with the blade reversed or looking at Fig. 4 from the opposite side;

Fig. 13 is a longitudinal sectional view through a single inlet fan and hollow shaft taken on the line 3—3 of Fig. 2;

2

Fig. 14 is a side elevation of one of the twelve blades used in this particular fan;

Fig. 15 is an edge elevation of Fig. 14;

Fig. 16 is a side elevation of another of the twelve blades used in this fan, six of them being as shown in this figure and six of the others being as shown in Fig. 14;

Fig. 17 is a half axial section through a fan similar to that shown in Fig. 3 but with a different kind of shroud construction, the several parts of which are individual to, integral with, and carried with the respective blades;

Fig. 18 is a partial section at right angles to the axis of Fig. 17 and a partial end elevation of the fan shown therein.

Fig. 19 is a side elevation of one of the twelve blades used in this particular fan;

Fig. 20 is an edge view of Fig. 19 looking from the right; and

Fig. 21 is an end view of the blades shown in Fig. 19 looking from the top.

In Figs. 1 and 2, 10 indicates a conventional form of masonry installation for a fan or blower within which is a metal casing 11 for a double inlet fan 12 mounted on a hollow, water-cooled shaft 13 journaled in bearings 14 and driven by a motor 15 through a V-belt drive 16. The inlet side of a water cooling unit is shown generally at 17, and the return side is shown generally at 18. Water cooling is ordinarily used in fan constructions for propelling high temperature fluids such as the gases recirculated in heat treating furnaces.

The detail of a double inlet fan is shown in Figs. 3—12, Sheets 2 and 3. The fan is composed of twelve blades 19, two circular shrouds 20, and two hub portions 21 assembled on the hollow shaft 13.

From the side views shown in Figs. 4 and 12, it will be seen that the fan blades in this instance are composed of a generally rectangular flat plate having the inner corners cut away at 22 to provide part of the inlet passages, and adjacent to these cut away corners there are legs 24 and 25 provided with feet 26 and 27 symmetrically arranged with respect to the legs 24 and 25 and the main body of the blade and having adjacent to each end holes or openings 28 and 29 (Fig. 5).

In this particular 24" fan, the legs 24 are 2 3/4" from the center line of the blades, the legs 25 are 3 3/8" from the center line of the blades, and the feet 26 and 27 are 5/8" thick measured along the axis of the fan. From this statement and a consideration of Figs. 5 and 12, it will be apparent that by reversing alternate blades in

the series of twelve, they can be brought into the relation shown best in the right half of Fig. 10, in which the adjacent ends of the feet 26 of adjacent blades overlap (compare Figs. 3 and 10). And thus the assembly in circular arrangement about the common axis of rotation may be secured together and to the hub members 21 by pins generally indicated at 30 (Figs. 3, 8, and 10). When thus assembled, the pins connect the circular arrangement of blades to form a chain about the common axis of rotation in which all of the corresponding parts are equidistant from that axis, and, as a natural result, if the several blades and pins are substantially the same throughout the series there will be dynamic balance in which the whole can expand and contract as one, and each with proper clearances can expand and contract individually while each blade is held against individual outward movement under the action of centrifugal force.

In this particular design, the pins 30 are given three diameters for three lengths of $\frac{5}{8}$ in., the intermediate diameter 31 being $\frac{7}{16}$ in. and the two end diameters 32 being $\frac{3}{4}$ in. The holes 28 and 29 in the feet 26 and 27 and the holes 33 in the flanges 34 of the hub members 21 are made to correspond with suitable clearances and tolerances. This arrangement not only interlocks the individual blades to each other in series, but also to the hub members and automatically makes the pins 30 fast against movement in any direction.

The hub members 21 are fixed to the shaft 13 by three driving keys 35 spaced equidistant about the axis of rotation and preferably fitted in keyways to contact at the sides only, which are made parallel. This arrangement of keys provides proper driving connection between the shaft and the hub members while the shaft remains comparatively cool due to the circulation of water, and the hub members get relatively hot due to contact with the recirculated gases and the other members of the fan.

The hub members are spaced from each other and held against binding on the assembled feet 26 and 27 by a hollow, cylindrical spacer 36 telescoped over the shaft 13. The left hub member 21 in Fig. 3 is seated against an integral shoulder 37 on the shaft and the right hub member is made fast by a collar 38 threaded on the hollow shaft set up against the hub member, and then backed off an amount corresponding to the calculated or empirically determined expansion. It is locked by lock washer 39 having a finger 40 in a groove 41 in shaft 13 and a finger 42 bent over into a slot 43 in a lock nut 44 also threaded on the shaft 13.

In some service, the assembly thus far described will be suitable without any shrouds. In others, shrouds will be appropriate and in many instances considered indispensable. They may be very conveniently carried upon the blades in such a manner that they float on the several blades subject, in the main, to centrifugal force alone, except in starting and stopping or in acceleration or deceleration. In one way of accomplishing this, at or adjacent to each side edge 45 each blade is thickened and provided with grooves 46 whereby at each side of each groove there appear ribs 47 and 48, the ribs 47 being relatively short and the ribs 48 being relatively long—approximately as long at the edges 45 as the shrouds are wide.

Each shroud 20 is a ring, here shown as provided with outwardly opening slots 49, twelve in

number, to receive the side edges of the several blades as the adjacent portions of the slots are received between the ribs 47 and 48. The shrouds are of uniform thickness to about the depth of the slots 49, and from there inwardly they are gradually thickened as indicated at 50 to provide additional strength for resisting the bursting tendencies of centrifugal force on the shrouds as a whole.

With the shrouds thus mounted on the outer portions of the blades at their side edges, the shrouds and those portions of the blades are free to expand and contract independently, and yet the twelve supports for the circular shrouds adjacent to the outer edge of the wheel serve to center the shrouds very accurately without putting any bending strains on the blades.

As an empirical rule, the slots 49 should not ordinarily be deeper than one-third of the radial depth of the shrouds, and they need not in fact be that depth for ordinary purposes.

When for any reason, such as the corrosive atmosphere and the high temperatures, it becomes necessary to use alloys in the blades that are likely to crack outwardly of the pins 30, a safeguard against the broken portion of a blade flying out under centrifugal force and doing damage to the assembly as a whole may be obtained by providing the slots in the shrouds opening from the inner side, or, better still, the interlocking connection may be made by special projections extending inwardly from the inner periphery of the shrouds and cooperating with suitable projections on the blades, an illustration of which will be found in a copending application, Serial No. 590,754, filed April 28, 1945, now Patent No. 2,428,768, issued October 7, 1947.

Figs. 13-16 (Sheet 4) show a single inlet fan corresponding in all other respects to the construction described in connection with Figs. 3-12 (Sheets 2 and 3) with the following exceptions: Six of the blades 219 correspond to the form shown in Fig. 14 and the other six to the form shown in Fig. 16 so as to provide for the overlapping and interlocking of the feet as described in connection with the double inlet fan and also to provide for the closure at the side opposite the single inlet, which is formed by the shrouds 120 (Fig. 13). Beyond these exceptions, it is deemed sufficient to merely add the corresponding reference numerals to Figs. 13-16.

Figs. 17-21 (Sheet 5) show a fan construction corresponding to that shown in Figs. 3-12 (Sheets 2 and 3), except as to the shrouds. In this instance, each blade 219 has a shroud section 60 at one side and a shroud section 61 at the opposite side whereby the blades are given a sort of H formation in cross-section at the outer portion, as will appear best in Fig. 21.

The several shroud portions 60 have machined faces 62 adapted to be received within the flanges 63 forming forks at the free edges of the shroud portions 61. The assembly of these several shroud portions 60 and 61 around the circular arrangement completes the shrouds and makes them in effect complete circles carried by the several blades with freedom for expansion radially and circumferentially and having their weight so evenly distributed equidistantly with respect to the axis of rotation as to give dynamic balance to the whole. Outside of this exception the construction is substantially the same as described in connection with Figs. 3-12 (Sheets 2 and 3).

Further details of this construction are given in

copending application Ser. No. 594,750, filed May 19, 1945.

According to the preferred practice, the hub portions, blades, shrouds, etc., are formed of a suitable alloy and machined to make all the corresponding parts substantially identical. After machining, the parts are annealed at a temperature above the highest to be expected in service in order to remove internal strains that might be released in service and throw the fan out of balance. By weighing the blades and a slight amount of fitting, the assembly can be readily given dynamic balance and the construction described will insure the maintenance of that balance in service as well as the necessary strength for a long period of service.

The choice of the alloy to be used will be effected by the temperature to be endured and the corrosive nature of the atmosphere, or the lack of any corrosiveness in the atmosphere. Metallurgists will understand that some alloys having a high resistance to corrosion do not have high strength at high temperatures and some sort of compromise will occasionally have to be made. These things will affect some of the clearances and other features of design and construction, but, as an example, the pins 30 should have a push fit—for example, not more than .002" clearance in the hole. The blades and shrouds shown in Figs. 3-12 should fit with tolerances of plus .002" minus .000". The hub members should fit the shaft with tolerances of plus .001" minus .000".

In the preferred construction, the pins 30 in the holes 28 and 29 in the feet 26 and 27 take all of the radial stress due to centrifugal forces, and the driving stress is taken by that portion of the pins entering the holes in the hub members. Of course, some engineers will prefer to vary this, and indeed some will wish to effect a more positive driving and stabilizing relation between the hub members and the blades by fitting the feet and, in some instances, the inner portions of the blades into slots in the hub members corresponding to the arrangement shown in copending application Ser. No. 589,565, filed April 21, 1945 now Patent No. 2,385,838, issued October 2, 1945. But, in the interest of brevity, specific illustration and description of those things have been omitted.

I claim:

1. In a centrifugal fan, a plurality of blades in circular arrangement about a common axis of rotation with the inner portions converging inwardly toward said axis and the outer portions diverging outwardly from said axis, hub members overlapping the assembled inner end portions of the blades, and means between each pair of adjacent blades for making said inner end portions of the blades fast to each other and to the hub portions to hold them against individual bodily movement outwardly due to centrifugal force and rotary movement relative to the hub portions.

2. In a centrifugal fan, a plurality of blades in circular arrangement about a common axis of rotation with the inner portions converging inwardly toward said axis and the outer portions diverging outwardly from said axis, hub members overlapping the assembled inner end portions of the blades, and means between each pair of adjacent blades for interlocking said inner end portions of the blades fast to each other and to the hub portions to hold them against individual bodily movement outwardly due to centrifugal force and rotary movement relative to the hub portions.

3. In a centrifugal fan, a plurality of blades in circular arrangement about a common axis of

rotation with their outer portions diverging outwardly from said axis and their inner portions converging toward said axis and overlapping in series about it, hub portions at either side thereof, and means between each pair of adjacent blades for making the overlapping inner end portions of the blades fast to each other and to the hub portions to hold them against individual bodily movement outwardly due to centrifugal force and rotary movement relative to the hub portions.

4. In a centrifugal fan, a plurality of blades in circular arrangement about a common axis of rotation with their outer portions diverging outwardly from said axis and their inner portions converging toward said axis and overlapping in series about it, hub portions at either side thereof, and means equidistant from the axis and between each pair of adjacent blades for making the overlapping inner end portions of the blades fast to each other and to the hub portions to hold them against individual bodily movement outwardly due to centrifugal force and rotary movement relative to the hub portions.

5. In a centrifugal fan, a plurality of blades in circular arrangement about a common axis of rotation with their outer portions diverging outwardly from said axis and their inner portions converging toward said axis and overlapping in series about it, hub portions at either side thereof, and pins between each pair of adjacent blades making the overlapping inner end portions of the blades fast to each other and to the hub portions to hold them against individual bodily movement outwardly due to centrifugal force and rotary movement relative to the hub portions.

6. In a centrifugal fan, a plurality of blades in circular arrangement about a common axis of rotation with their outer portions diverging outwardly from said axis and their inner portions converging toward said axis and overlapping in series about it, and pins between each pair of adjacent blades fastening together said overlapping inner end portions of the blades in a circuit about the axis to hold the blades against individual bodily movement outwardly due to centrifugal force.

7. A fan blade comprising a generally rectangular flat body having its lower corners cut away, legs extending from the inner edge of the body adjacent to the cutaway corners, and a foot on each leg symmetrical with respect to it and extending transversely to it.

8. A fan blade comprising a generally rectangular flat body having legs extending inwardly from its inner end portion and located unequal distances on opposite sides of the center line of the body, and feet projecting laterally from each side of each leg, whereby a plurality of blades are adapted to be alternately reversed about an axis of rotation with adjacent feet overlapping for connection together by means extending through said feet.

9. In a centrifugal fan, a plurality of blades in circular arrangement about a common axis of rotation with the inner portions converging inwardly toward said axis and the outer portions diverging outwardly from said axis, a pair of legs extending inwardly from the inner end portion of each blade with the legs of each pair located unequal distances on opposite sides of the center line of each blade, feet projecting laterally from each side of each leg, adjacent blades being reversed whereby the feet of each blade overlap the feet of the adjacent blade, hub members overlapping the assembled inner end portions

of the blades, and means extending through each pair of overlapping feet and through the hub members for holding the blades together and to the hub members against individual bodily movement outwardly due to centrifugal force and against rotary movement relative to the hub members.

10. In a centrifugal fan, a plurality of blades in circular arrangement about a common axis of rotation with the inner portions converging inwardly toward said axis and the outer portions diverging outwardly from said axis, a pair of laterally projecting feet formed on the radially inner portion of each blade on each opposite side of the radial center line of the blade with one pair of feet axially farther from said center line than the other pair whereby the feet of each blade in the circular arrangement overlap the

feet of the adjacent blade, hub members overlapping said feet, and pins extending through each pair of overlapping feet and through the adjacent hub member for holding the blades together and to the hub members against individual bodily movement outwardly due to centrifugal force and against rotary movement relative to the hub members.
